DETACHABLE TAG

Lewis E. Williams, Long Beach, Calif.

Application August 20, 1934, Serial No. 740,612

2 Claims. (Cl. 40—23)

This invention relates to tags or tickets for attachment to fabrics, particularly tags for use on garments, cloth and the like, to show price, size, the grade of material, or any other desired information.

A broad object of the invention is to provide a tag that can be quickly attached or removed while at the same time resisting accidental removal.

10 Another object is to provide a detachable tag having pointed metal fastening elements so arranged that it is difficult, if not impossible, for an operator to prick himself while attaching or removing a tag or while handling a garment to which the tag is secured.

To the best of my knowledge, it has been the practice heretofore to secure tags to clothing either by sewing the corners of the tag to the fabric with thread and needle or by using a U-shaped wire clip which is attached to the tag during manufacture, the points of the clip being forced through the fabric to which the tag is to be attached and bent back on the other side of the fabric. Sewing is objectionable because it is slow and expensive and also because the thread often breaks, or the end pulls out, thereby permitting the tag to become detached. The tags having wire clips thereon that have been employed heretofore are subject to the criticism that the sharp points are not protected and operators frequently prick their fingers in attaching or removing the tags or in handling the garments to which the tag is to be attached.

35 In accordance with the present invention I avoid the foregoing difficulties of the tags heretofore used by imbedding a spring wire in the tag (preferably by forming the tag from two layers of paper or cardboard glued together with the wire positioned between the two layers) and extending one or both ends of the wire out of the tag and pointing the ends of the wire and so curving them that they are directed toward one face of the tag, whereby they are adapted to grip or clamp a fabric against the tag. With this arrangement the point or points of the wire are protected and at the same time a means for securely locking the tag to the fabric is provided.

50 The invention may be employed in a number of different types of tags, various modifications being resorted to for different purposes. A full understanding of these various modifications may be had from the following detailed description which refers to the drawing.

In the drawing:

Fig. 1 is a plan view of a tag in accordance with the invention which is adapted to slip over the edge of a piece of fabric;

Fig. 2 is a detail cross section of the tag shown in Fig. 1, showing more clearly the mode of attachment of the tag to a fabric;

Fig. 3 is a perspective view of the wire element employed in the tag shown in Fig. 1;

Fig. 4 is a sectional view of another form of tag in accordance with the invention which is adapted to be secured to the edge of a fabric surface;

Fig. 5 is a perspective view of the wire element employed in the tag shown in Fig. 4;

Fig. 6 is a sectional view through a portion of a tag of the general type shown in Fig. 4 but differing therefrom in detail;

Fig. 7 is a perspective view of the wire element employed in the tag shown in Fig. 6;

Fig. 8 is a sectional view showing still another modification of the general type of tag illustrated in Fig. 4;

Fig. 9 is a perspective view of the wire element of the tag shown in Fig. 8;

Fig. 10 is a perspective view of a tag in accordance with the invention which is adapted to be secured to a fabric surface at any point thereon; and

Fig. 11 is a detail view showing a modified form of construction for use in connection with the type of tag shown in Fig. 10.

Referring first to Figs. 1, 2, and 3, I have shown a folded tag which is adapted to open like a book to receive the edge and adjacent portion of a piece of fabric to which the tag is to be attached. The tag proper comprises two layers of thin sheet material 1 and 2, respectively, such as cardboard, the inner layer being adapted to contact the fabric to be tagged and the outer layer constituting the visible surface bearing the information to be conveyed. Thus as shown in Fig. 1, the outer surface of the tag has been printed to show the size, the lot and the number of the article to be tagged.

Positioned between the inner and outer layers of cardboard 1 and 2, respectively, is a reinforcing element 3 of spring wire, the major portion of this element being firmly imbedded between the two layers of cardboard, as shown in Fig. 2. One half of the element 3, identified by the reference numeral 4, which is adapted to be entirely located within one-half of the tag, is shaped to constitute an open frame, thereby giving a reinforcement to a substantial area of the portion of

the tag in which it is located. The other portion of the element 3, identified by the reference character 5, is straight through the major portion of its length and extends midway through the other half of the tag to a point adjacent the center of the tag, where it is curved inwardly to project through the inner layer 1 and is pointed and hooked, as indicated at 6, to penetrate and grip a fabric inserted between the two halves of the tag.

The element 3 is preferably coiled, as shown at 7, at the folded edge of the tag to provide increased resilience. The tension of the element 3 normally maintains the two halves of the book-shaped tag in close relationship to each other. However, by initially separating the tip of the tag, it may readily be forced over the edge of a piece of fabric, for instance, over the cuff of a coat. Because of the direction in which the point 6 is curved, little resistance is encountered as the tag is forced over the fabric. However, the tag is securely anchored if attempt is made to pull it off the fabric because the hook 6 is forced firmly into the fabric.

When it is desired to remove the tag, this may be done by inserting the finger between that portion of the tag containing the hook 6 and the fabric, thereby maintaining the hook 6 clear of the fabric while the tag is pulled clear.

Referring next to Figs. 4 and 5, there is shown a tag 8, which is likewise formed of two layers of pasteboard 9 and 10, respectively, glued together with a portion of a wire element 11 imbedded therebetween. As clearly shown in Fig. 5, the wire element 11 is of irregular outline, comprising straight portions 12, 13, 14, 15, 16, and 17, all of which lie in a common plane and are contained between the two cardboard elements 9 and 10.

Beyond the section 17 there is a straight section 18 extending through the cardboard layer 10, this portion 19 extending at right angles to the plane containing the previously recited sections, and merging into a straight section 19 extending upwardly parallel to the face of the tag but spaced therefrom. This section 19 in turn merges into a straight section 20 which extends through an aperture 21 provided therefor in the tag to the opposite side of the tag, where it merges into another straight section 22, which in turn merges into a straight section 23 extending back through a second aperture 24 in the tag. The section 24 merges into a straight section 25 which is substantially in line with the section 19 and merges into a terminal section 26 which is pointed and is juxtaposed to the face of the tag substantially at the intersection of the sections 14 and 15 of the wire. This tag is attached to a fabric by pressing on the exposed section 22 of the wire, thereby moving the point of the wire clear of the tag to permit insertion of the edge of a fabric between the point and the tag. Thereupon, release of the pressure on the section 22 permits the point 26 to be moved toward the tag, thereby gripping the fabric. Obviously the tag may be readily removed by merely repeating the operation described for shifting the point of the wire away from the tag, and withdrawing the fabric.

A simplified form of the tag just described is illustrated in Figs. 6 and 7. In this instance it will be observed that the wire element comprises straight sections 27, 28, 29, and 30, positioned in a common plane and adapted to be imbedded between the two layers of the tag.

The wire beyond the straight section 30 is extended substantially at right angles thereto as a straight section 31, out through the edge of the tag, at which point it is coiled as shown at 32, then curved as shown at 33 where it merges into a straight portion 34 extending substantially at right angles to the plane of the tag and passing through a hole 35 provided therefor in the tag. The straight section 34 merges into a straight section 36 substantially parallel to the tag, which merges into the tip 37, which is pointed and normally held against the tag by the inherent resilience of the wire. It will be observed that the tip 37 constitutes a clip which may be opened for the insertion of the edge of a fabric to which the tag is to be attached by pressing the curved portion 33 of the wire toward the tag.

In Figs. 8 and 9, there is shown a modification of the construction described in connection with Figs. 4, 5, 6, and 7 in which the wire, instead of being extended through a hole in the tag, is brought back over the top of the tag. Thus the wire comprises straight sections 40, 41, 42, 43, 44, and 45, all lying in the plane of the tag 30 and imbedded between the two layers of the tag. The end of the section 45 projects through the edge of the tag, beyond which point the wire is coiled, as shown at 46, curved down over one side of the tag to constitute a handle portion 47, then doubled back on itself and extended over the top of the tag as a curved portion 48, which merges into a straight portion 49, which terminates in the tip portion 50. This modification is actuated to displace the point 50 from the tag by depressing the handle portion 47 toward the tag. When pressure on the handle 47 is released, the resilience of the wire engages the pointed end 50 of the wire firmly in a fabric positioned thereunder against the tag.

All of the tags so far described are adapted to be slipped over the edge of a fabric. In Fig. 10 there is disclosed a tag which is adapted to be secured to a fabric surface at any point 45 thereon. It comprises two sheets of cardboard 51 and 52, respectively, glued together, between which there are anchored two similar wire elements 53 and 54 positioned adjacent opposite ends of the tag. Each of the elements 53 and 54 comprises two straight sections 55, and two straight sections 56 lying in the same plane and imbedded between the two layers of the tag. The sections 56 extend beyond the ends of the tag and merge into straight sections 57, which extend parallel to the plane of the tag but at right angles to the sections 56. These sections 57 in turn merge into straight sections 58 which extend substantially parallel to the sections 56 and merge into the curved hook portion 63, the sharpened tips of which bear against the face of the tag. To secure the tag to a fabric surface, the hooked tips 63 are displaced away from the surface of the tag by exerting pressure on the sections 57, thereby permitting a small fold of the surface of the fabric to which the tag is to be attached to be engaged between the surface of the tag and the tip 63. Thereafter, release of the sections 57 causes the hooks 63 to firmly clamp the fabric against the surface of the tag. The arc through which the hook 63 can be swung may be increased by introducing a coil 64 between the sections 56 and 57, as shown in the detailed view of Fig. 11.

It will be observed that in all of the modifications of the invention described the pointed tips of the wires are directed toward a face of the tag so that the fabric is clamped firmly between the tip and the tag. Furthermore, this construction makes it almost impossible for an operator to contact the sharp tips of the wires with his fingers either while attaching or removing the tags or while handling garments to which the tags are secured.

Furthermore, in each type of tag described it will be observed that that portion of the wire which is imbedded between the two layers of the tag extends over a relatively large area within the tag and furnishes a very desirable reinforcement for stiffening the tag.

Although numerous embodiments of the invention have been described, it will be apparent to those skilled in the art that various other changes may be made without departing from the spirit of the invention. The latter is therefore to be limited only as set forth in the appended claims.

I claim:

1. A tag of sheet material folded in book fashion, in combination with means for attaching the tag to a fabric edge comprising a length of

spring wire, a major portion of which is imbedded within said tag, one end portion of said wire being imbedded in one leaf of said tag and bent into a closed loop to reinforce a substantial area of said leaf, said wire extending within said one leaf to the folded edge of the tag, and being coiled at the fold to provide increased resilience, the end portion of said wire beyond said coil being imbedded in the other leaf of the tag and the tip extending through the inner 10 surface of the leaf into the space between the two leaves for engaging a fabric edge over which said tag may be placed.

2. A tag comprising a sheet of material folded into book shape whereby it is adapted to be 15 slipped over an edge of a fabric, having a reinforcing and anchoring means therein comprising a spring-wire element the greater part of which is imbedded in said tag, the wire extending from the folded edge of the tag into the two juxtaposed leaves of the tag and a point on the wire in one of said leaves extending through the inner surface of the leaf into the space between the leaves for engaging a fabric inserted between the leaves, said spring wire element being con- 20 figured to urge said leaves together.

LEWIS E. WILLIAMS.
